DESIGN FOR A CAMERA COVERING

William L. Lawson, Brooklyn, N. Y.

Application November 5, 1935, Serial No. 59,395

Term of patent 7 years

To all whom it may concern:

Be it known that I, William L. Lawson, a citizen of the United States, residing at Brooklyn, in the county of Kings and State of New York, have invented a new, original, and ornamental Design for a Camera Covering, of which the following is a specification, reference being had to the accompanying drawing, forming a part thereof.

Figure 1 is a perspective view of the covering in closed position illustrating one side thereof.

Figure 2 is a perspective view of the covering in closed position and illustrating the other side thereof.

Figure 3 is a top plan view of the covering in the unfolded or expanded position.

The outer surface of the case is stippled to represent graining.

I claim:

The ornamental design for a camera covering, as shown and described.

WILLIAM L. LAWSON.
